CLAIMThe ornamental design for a ceiling fan light cage, as shown
and described.**DESCRIPTION**

FIG. 1 is a bottom perspective view of a ceiling fan light cage in the environment of a ceiling fan, showing my new design;

FIG. 2 is a top perspective view of the ceiling fan light cage without the ceiling fan environment;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

Portions of the ceiling fan light cage and the ceiling fan environment are shown in broken lines. Portions of the ceiling fan light cage and ceiling fan environment shown in broken lines form no part of the claimed design.
